CONICAL FURNACE

John S. Wallis and John W. Throckmorton, New York, N.Y., assignors, by mesne assignments, to Yuba Consolidated Industries, Inc., San Francisco, Calif., a corporation of Delaware

Filed Jan. 28, 1959, Ser. No. 789,584

5 Claims. (Cl. 122—356)

This invention relates to upright heaters which are usually employed in large sizes for raising the temperature of oil or gas to elevated temperatures such as are useful and necessary for cracking, reforming and various other analogous operations.

In our United States Patent 2,294,254, issued August 25, 1942, we have shown and described a heater of this general type in which the walls of the furnace chamber slope inwardly from the bottom to the top, but in this case the slope is slight and the heat exchange tubes within the chamber are arranged substantially in the same fashion as if the chamber walls were cylindrical.

The heater of this invention has a number of distinct advantages over previous structures, and certain of the objectives are as follows:

(1) The tall upright furnace chamber has a distinct inward slope from bottom to top, and continues beyond the convection section of the heater to form a portion of the stack. In this way the heater has a very broad base relative to the top and the frusto-conical shape of the chamber and the chamber walls themselves are entirely adequate to support the stack portion and the usual tall stack without requiring any structural steel supporting elements such as are usually mounted on the outside of the chamber walls. This results in a very substantial saving in the investment cost and increases the stability of the heater.

(2) The heat exchange coils are spaced inwardly from the chamber wall, and at the bottom they are spaced from each other in the form of a single circle. At the top, on the other hand, the chamber is narrowed down to such an extent that a special arrangement of the tubes is made as hereinafter described.

(3) A frusto-conical baffle of somewhat smaller diametrical dimensions is hung in the upper end of the heater with its smaller end upward and its larger end downward to conform to the contour of the upper end of the furnace chamber. This baffle is closed at the top and is open at the bottom so as to save metal.

(4) Certain spaced tubes extend all the way to the top of the heater and others extend only close to the bottom of the baffle, and in this fashion the proper spacing of the tubes is maintained in spite of the wide difference in diameter between the bottom and top of the heater.

Referring to the drawings:

Figure 1 is a partially sectional elevation with certain of the heating tubes omitted for clarity;

Fig. 2 is a sectional plan view on the line 2—2 of Fig. 1 which shows the arrangement of the heat exchange tubes at the bottom of the heater;

Fig. 3 is a sectional plan view on the line 3—3 of Fig. 1 which shows the tube arrangement near the top of the furnace chamber but just below the baffle;

Fig. 4 is a partially sectional plan view on the line 4—4 of Fig. 1 which shows the tube arrangement in the convection section formed between the baffle and the adjacent wall of the furnace chamber;

Fig. 5 is a view corresponding to that of Fig. 1 of the

2

heater which constitutes another embodiment of this invention;

Fig. 6 is a sectional plan view taken on the line 6—6 of Fig. 5; and

5 Fig. 7 is a partially sectional plan view taken on the line 7—7 of Fig. 5.

Fig. 8 is a detailed sectional view taken on the line 8—8 of Fig. 5.

Referring specifically to Figs. 1 to 4, the heater illustrated comprises a frusto-conical combustion chamber 10 which is built of relatively heavy steel plate and has a refractory lining 11 on its inner surface. A substantially horizontal bottom plate 12 is welded or otherwise secured to the chamber walls at the bottom and has one or more upshot burners 13, four being illustrated as shown in Fig. 2, mounted in the bottom plate so as to provide a column of flame and hot gases which rises upward along the central axis of the heater.

The chamber is supported from foundation 14 by a plurality of structural steel legs 15 which are welded to the chamber wall near the bottom and extend to the foundation. Legs extend as a continuation of the contour of the furnace chamber so that they are widely spread apart at the foundation and support the bottom plate of the furnace chamber at sufficient height to enable attendants to stand erect below the bottom of the heater for the purpose of adjusting the burners or performing any other necessary functions.

A plurality of heat exchange tubes 16, 17 and 18 are spaced inwardly from the furnace chamber walls and are equally spaced from each other in a circular bank at the bottom of the heater as shown in Fig. 2. The tubes 16 and 18 and 17 and 18 are interconnected at the bottom by return bends which are supported in grooves in the bottom plate 12 in the same manner as tubes 50 and 51, as shown in Fig. 8.

Tubes 18, which in the structure illustrated are arranged in pairs that are separated from each other by one tube 16 and one tube 17, extend parallel to the chamber wall all the way to the top of the chamber and are interconnected by return bends 19 as shown in Fig. 4. The taper of the furnace chamber is such that the tubes 18 are equally spaced from each other in a circular bank at the top as shown in Fig. 4.

45 In order to accommodate the tubes 16 and 17, which cannot be extended all the way to the top of the heater because of lack of space, they are interconnected by return bends 20 just below the convection section of the heater which is hereinafter described.

At this point, as shown in Fig. 3, there is room for the tubes 16 and 18 to be spaced in a circular bank, whereas the tubes 17 are sloped from the single circle of Fig. 2 at the bottom to an inner circle at the return bends as shown in Fig. 3.

55 A convection section of the furnace is formed at the upper end by a frusto-conical baffle 25 which follows the contour of the furnace chamber walls but is diametrically smaller in dimensions so as to leave an annular frusto-conical space 26, through which the upper ends of the tubes 18 extend. In this section of the heater the tubes 18, have extended surface elements as shown at 27. The baffle 25 is closed at the top by a plate 28 but is open at the bottom as shown in Fig. 1.

The baffle 25 is hung by suspension rods 29 from lugs 30 on the outer surface of the stack portion 31 which is a continuation of the frusto-conical furnace chamber and constitutes a support for the stack 32.

In operation of the burners 13 discharge axially upward hot flame and combustion products which soon fill the inside of the baffle 25 and then overflow and pass at unusually high velocity through the annular space 26 of the

convection section and are thence discharged through stack portion 31 into stack 32.

The tubes 16, 17 and 18 are all heated primarily by radiation from the bottom of the heater to the bottom of the baffle, radiated heat being supplied directly from the flame and not gases in the center and by reradiation from the refractory lining 11 which is heated by direct radiation from the flame and hot gases to a very high temperature and reflects its heat.

The tubes are interconnected in any suitable manner but preferably so that there is a single inlet 35 and an outlet 36 located in the bottom of the furnace below the bottom plate 12.

Referring now to Figs. 5, 6 and 7 of the drawings, the structure here shown is similar in many respects to that of Figs. 1 to 4, inclusive, and the same reference characters indicate the same parts. In this structure the baffle 37 is smaller in its dimensions but similar in its shape to that of baffle 25 so that a wider annular space 38 is provided and is adequate to receive a double row of fin tubes arranged in circles 39 and 40 as shown in Fig. 7 and interconnected at the top by return bends 41.

The tubes in circle 40 are spaced closer together than the tubes in circle 39 so that the same number of tubes is accommodated in each circle and the return bends 41 are inclined so that the tubes of the circle 40 are not directly in the same radius as the corresponding tubes in circle 39, the arrangement being such that the fin tubes closely fill the annular space 38 which constitutes the convection section of the heater.

Tubes which are designated 50 and 51 are equally spaced in a circular bank at the bottom of the heater as shown in Fig. 6, and tubes 50 slope inwardly so that their upper ends are in the inner bank 40, whereas the tubes 51 extend all the way parallel to the inner wall of the furnace chamber and terminate in tube circle 39. At the bottom the tubes 50 and 51 are interconnected by return bends 50a supported in grooves 51a in the bottom plate 12. In this way the weight of the tubes is carried by the bottom plate.

In the operation, burners 13 discharge flame and hot combustion gases upward in an axial direction, which gases fill the baffle 37, overflow and flow around and among the fin tube sections 60 of the tubes 50 and 51 at high speed.

The tubes are heated by radiation from the central flame and hot gases and by reradiation from the refractory lining 11 of the furnace chamber 10.

The structure illustrated is relatively low in cost because of the absence of the usual structural steel supports which normally extend the entire length of the heater and carry the stack at the top. The wide spread of the heater at the bottom gives it unusual stability.

In the section of the heater below the baffle where the tubes are interconnected at the top by radially extending return bends in the structure of Fig. 1 and approach radial spacing in the arrangement of Fig. 5, the tubes are supplied with heat both by radiation and by convection, whereas lower down in the furnace chamber the tubes are heated almost entirely by radiation.

The furnace of this invention with a large base and a very small opening at the top has the distinct advantage of producing an unusually high gas velocity through the convection section, with a consequent increased rate of heat transfer.

The drawings and the specific embodiments described are intended to be illustrative only and constitute what we now regard as the best embodiment of our invention. Other modifications may be made without departing from the spirit of the invention, and only such limitations should be imposed as are indicated in the appended claims.

What we claim is:

1. An upright heater comprising a frusto-conical combustion chamber having a large circular bottom plate, at

least one burner mounted therein and discharging flame and combustion gases upwardly in a substantially vertical path within the chamber, a plurality of heat exchange tubes spaced from each other and from the inner wall 5 of the frusto-conical combustion chamber and having their bottom ends arranged in a single circular row, a frusto-conical baffle depending from the top of the combustion chamber and corresponding in shape to the upper end of said chamber but of smaller diametrical dimensions to provide a frusto-conical annular convection chamber, a uniformly distributed number of said heat exchange tubes being elongated to extend through the convection chamber and having extended surface elements in said convection chamber, return bends interconnecting the elongated tubes at their top ends, radially extending return bends interconnecting the remainder of said heat exchange tubes in pairs at the top of the combustion chamber below the convection chamber and circumferentially extending return bends interconnecting the bottom ends of the tubes in the circular row at the bottom of the heater.

2. An upright heater comprising a frusto-conical combustion chamber having a large circular bottom plate, at least one burner mounted therein and discharging flame and combustion gases axially upward within the chamber, an upright heating coil within the chamber having a plurality of long heat exchange tubes spaced from one another and from the walls of the combustion chamber, the bottom ends of the tubes being arranged in a single 20 large circular row, circumferentially extending return bends interconnecting the bottom ends of the tubes in pairs in said large circular row, certain uniformly distributed ones of said tubes being inclined inwardly whereby the top ends of the tubes form two small concentric 30 circular rows and radially extending return bends interconnecting the tops of the tubes in pairs between the two circular rows.

3. A streamlined upright heater comprising a tall frusto-conical furnace chamber with a broad base and 40 the small end of the cone upward, a frusto-conical stack portion at the top of the furnace with its lower end sized to correspond to the small end of the furnace cone and its side walls constituting a continuation of the furnace wall, legs attached to the furnace cone at the bottom extending downwardly and outwardly to form a continuation 45 of the furnace wall and holding the cone at a spaced position above the foundation, a horizontal bottom plate closing the furnace shell at the bottom of the cone, one or more upshot burners mounted in the bottom plate and 50 adapted to discharge flame and combustion products axially upward within the conical furnace chamber, a plurality of straight heat exchange tubes within the cone and spaced from its wall, said tubes being equally spaced from each other and their lower ends being arranged in a single circular row at the bottom of the furnace and 55 interconnected in pairs by circumferentially extending return bends mounted in grooves in the bottom plate and interconnected in pairs by radially extending return bends at their top ends to form two concentric circular rows of tube ends near the top of the furnace.

4. A streamlined upright heater comprising a tall frusto-conical furnace chamber with a broad base and the small end of the cone upward, a frusto-conical stack portion mounted on the top of the furnace with its larger end sized to correspond to the small end of the frusto-conical furnace chamber and its side walls constituting a continuation of the frusto-conical furnace chamber wall, legs attached to the frusto-conical furnace chamber at the bottom extending downwardly and outwardly to form a continuation 65 of the frusto-conical furnace chamber wall and holding the said furnace chamber at a spaced position above the foundation, a horizontal bottom plate closing the furnace shell at the bottom of the cone, one or more upshot burners mounted centrally in the bottom 70 plate and adapted to discharge flame and combustion 75 products axially upward within the conical furnace chamber.

products axially upward within the frusto-conical furnace chamber, a plurality of straight heat exchange tubes within the frusto-conical furnace chamber and spaced from its wall, the bottom ends of said tubes being equally spaced from each other in a single circular row at the bottom of said furnace chamber and interconnected at their upper ends to form two concentric circular rows near the top of the furnace chamber and extended surface means on the tubes near the upper end of the furnace chamber adapted to form a convection section of the heater.

5. A streamlined upright heater comprising a tall frusto-conical furnace chamber with a broad base and the small end of the cone upward, a frusto-conical stack portion mounted on the top of the furnace with its larger end sized to correspond to the small end of the furnace cone and its side walls constituting a continuation of the furnace wall, legs attached to the furnace cone at the bottom extending downwardly and outwardly to form a continuation of the furnace wall and holding the furnace chamber at a spaced position above the foundation, a horizontal bottom plate closing the furnace shell at the bottom of the cone, one or more upshot burners mounted in the bottom plate and adapted to discharge flame and

10 combustion products axially upward within the frusto-conical furnace chamber, a plurality of long, straight heat exchange tubes within the cone and spaced from its wall, the bottom ends of said tubes being equally spaced from each other in a single circular row and interconnected in pairs at the bottom of the furnace and said tubes being spaced in two concentric circular rows and interconnected in pairs at their upper ends, a frusto-conical baffle shaped to correspond to, but of smaller dimensions than, the upper end portions of the furnace to form a narrow annular convection section, said baffle having its upper smaller end closed by a top plate and its lower end open, and extended surface means on the tubes at the upper end of the furnace where they extend into the convection section.
